POWDER SPRAYER

Joseph W. Cimbura, Newport, and Eben C. Ives, St. Paul, Minn., assignors to Mueller Can and Tube Co., St. Paul, Minn., a corporation of Minnesota

Application April 2, 1945, Serial No. 586,130

8 Claims. (Cl. 222—193)

1

Our invention relates to powder sprayers and has for an object to provide a powder sprayer capable of operation in any desired position.

Another object of the invention resides in providing a powder sprayer in which the powder is contained in separate closed receptacles adapted to be bodily inserted into the device when desired for use.

Another object of the invention resides in providing a powder sprayer including pumping means and in which leakage of powder out of the same through the pumping means is entirely prevented.

A feature of the invention resides in providing a container for the powder receptacle and associated with the pumping means and in further providing an air pervious disc between the pumping means and interior of the container.

Another object of the invention resides in providing a valved air inlet between the pumping means and container and in disposing the air pervious over such inlet.

Other objects of the invention reside in the novel combination and arrangement of parts and in the details of construction hereinafter illustrated and/or described.

In the drawings:

Fig. 1 is an end view of a powder sprayer illustrating an embodiment of our invention.

Fig. 2 is a longitudinal sectional view taken on line 2—2 of Fig. 1.

Fig. 3 is a cross sectional view taken on line 3—3 of Fig. 2.

Fig. 4 is a cross sectional view taken on line 4—4 of Fig. 2.

Fig. 5 is a perspective view of the powder receptacle removed from the case.

In the use of powder sprayers in which the pump forms a part of the device, considerable loss of powder may occur through the pump. The instant invention provides a construction whereby this disadvantage may be overcome in an exceedingly simple and effective manner.

Our invention comprises a receptacle for powder indicated in its entirety by the reference numeral 10 and which is disposed within a case or container 11. Associated with this container is a pumping cylinder 12, by means of which air is forced into the device to create suction therein and draw powder into the air stream for discharge through the discharge outlet of the container. These various parts will now be described in detail.

The container 11 consists of a sleeve 13 of tubular material, such as paper which has a closure 14 at its lower end and a closure 15 at its upper

2

end. The closure 14 is preferably constructed of metal and is formed with a flange 16 which is crimped to the lower end of the sleeve 13 and which lies substantially within the confines of the outer surface of said sleeve, so as to provide a flush construction for coaction with the pumping means, as will be presently more fully described. This closure, as shown in Fig. 4 has a central opening 17 in the same serving as an air inlet through which the air pumped by the pump 12 may enter into the container 11.

For closing the other end of the case 13, a metal ring 18 is employed which encircles the sleeve 13 and is provided with a flange 20 crimped to the outer end of said sleeve and a tubular member 21 overlying said sleeve. The ring 18 has an opening 22 in the same surrounded by a lip 23. The lip 23 is pressed into the body of the sleeve 13 and lies substantially flush with the interior surface of said sleeve. The opening 22 gives access to the interior of the case 11, and the receptacle 10 is insertable into case 10 through this opening. The closure 15 is in the form of a cap and is constructed of metal having an end wall 24 and a flange 25 issuing outwardly therefrom. The flange 25 engages the lip 23 of the ring 18 and forms a fluid tight connection therewith. The tubular member 21 is held attached to the sleeve 13 by means of the ring 18 and in addition, may be glued to said sleeve if desired.

The receptacle 10 consists of a tubular body portion 26 which is closed at its upper and lower ends by means of caps 27 and 28. These caps are identical in construction and only the cap 27 will be described in detail. This cap consists of a disc-like portion 29 with a flange 30 extending outwardly therefrom. Said flange is crimped about the end of the body portion 26 and is preferably imbedded in the material of said body portion, so that the same lies flush with the outer surface thereof. The disc-like portion 29 has a boss 31 thereon which projects outwardly therefrom and lies in the plane of the edge of the flange 30 which serves a purpose to be presently more fully described. The body portion 26 of receptacle 10 is somewhat smaller than the sleeve 13 and forms with said sleeve an annular passageway 32 through which powder and air may pass in leaving the sprayer. The body portion 26 has holes 33 and 34 at the upper and lower ends thereof which communicate with the passageway 32 and by means of which powder within the receptacle 10 may be discharged into said passageway.

The cap 27 of receptacle 10 is spaced from the closure 15 to provide a chamber 134 therebetween at the upper end of the device, which communi-

cates with the passageway 32. The boss 31 of cap 27 engages a number of projections 35 formed on the under side of the portion 24 of closure 15 and serves to form in conjunction therewith a number of radial passageways 37 which communicate with the chamber 134 and lead to the center of the device. The portion 24 of the closure 15 has at its center a discharge opening 36. This opening communicates with the passageways 37 formed between the projection 35. It will hence readily be comprehended that any powder entering the passageway 32 is discharged through the discharge opening 36 when air is forced along passageway 32.

The cap 28, at the lower end of the receptacle 19 falls short of the closure 14 for case 11 to provide a pressure chamber 38 therebetween. This pressure chamber also communicates with the passageway 32. Within this chamber and overlying the closure 14 is a felt disc 39 which fits snugly against the inner surface of the sleeve 13 of container 11 and which engages the marginal portion of closure 14 at the opening 17 therein. Superimposing this disc is a flapper valve 41 which is best shown in Fig. 4. This flapper valve has portions 142 which fit loosely against the inner surface of the sleeve 13 and is cut away adjoining these portions to provide openings 143 through which air may pass into the chamber 38. The felt disc 39 is pervious to air but impervious to powder. It will readily be comprehended that the disc 39 may be constructed of any suitable material having the desired characteristics. When air is forced through opening 17, the same passes through the felt disc 39 at right angles to the surface thereof and escapes through the openings 43 in valve 41 and into the chamber 38.

The pump cylinder 12 consists of a tubular member 42 constructed of paper which has a closure 43 secured to the outer end thereof. This closure is preferably formed of metal and has a flange 44 crimped about the outer end of said tubular member. The tubular member 42 and the closure 43 constitute a cylinder which, acting in conjunction with the container 11, which serves as a piston form a pump means having a pump chamber 45 in which air may be compressed when said cylinder is moved toward the closure 14 of container 11. The closure 43 has an air inlet 46 which is adapted to communicate with the chamber 45. Overlying the closure 43 is a valve indicated in its entirety at 47 in Fig. 3. This valve consists of a disc 48 constructed of paper or some similar material which is formed with a crescent shaped cut 49 dividing the disc into an annular portion 51 resting upon the closure 43 and a central portion 52. The said disc is further weakened along a line 53 so that the central portion forms a hinged flapper valve for controlling the flow of air through the inlet 46. When the cylinder 12 is drawn outwardly, valve 47 opens to permit entry of air into the chamber 45. Upon reversal of movement, the flapper valve 52 closes the inlet 46 and the air is forced into the air chamber 38 through the air passageway 17 in closure 14 through the felt disc 39 and through the openings 43 formed in the valve member 41.

The powder to be dispensed from the device is furnished to the consumer packaged in the receptacle 10 which is filled with powder at the factory. For this purpose, the tubular body portion 26 is covered with a wrapper not shown in the drawings which covers the discharge openings 33 and 34. The cap 27 is first omitted and after filling, the said cap applied to completely close

said receptacle. A package is thus formed of powder which can be sold independently of the container and pump and which can be placed into the container by the user. In order to use the device, it is merely necessary to remove the closure 15, punch through the outer wrapper of the receptacle 10 at the locality of the discharge openings 33 and 34 therein to clear the same, and then insert the filled receptacle within the container and apply the closure 15 thereto. Due to the fact that the receptacle 10 is the same at both ends, it is immaterial which end is first inserted into the container 11.

When the sprayer is first constructed at the factory, a wrapper is preferably placed about the pumping cylinder 42 and the tubular member 18 connecting these members together. When the device is to be used, the wrapper is severed at the joint between the cylinder 12 and the said tubular portion to free the said cylinder and permit of operation of the same. When the complete device is sold to the consumer, the receptacle 10 is inserted into the container 11 without perforation of the wrapper about the said receptacle and the closure 15 must first be removed and the receptacle 10 withdrawn from the container 11 and the wrapper thereof perforated before the device can be used. Upon replacement of the receptacle 10 after perforation and also replacement of the closure 15, the device is then ready for use. To operate the device, it is merely necessary to pump the cylinder 12 back and forth. This successively draws air into the pressure chamber 45, compresses the air and forces the air through the valve opening 17 through the felt disc 39 and into the chamber 38. From this chamber, the air passes through the annular passageway 32 and into the chamber 134. As the air enters the passageway 32, it expands and causes suction in the powder outlets 34 and/or 33 which draws powder into the passageway 32 and mixes the same with the air. The powder laden air is then directed through the passageway 37 and discharged from the outlet 36. In the drawings, the device has been illustrated in upright position. It will, however, become apparent that the device may be tilted or inverted. In any position of the device, the powder openings 33 and 34 will always be in a position to discharge powder into the passageway 32. Thus, the device may be held at any angle or position and thus cause flow of powder from the discharge opening 36.

While we have described the powder as entering the passageway 32 through suction caused by the air passing through said passageway, it will readily be comprehended that a certain amount of powder sifts into said passageway through the disturbance set up in the device by the manipulation of the pumping cylinder 12 and also by the action of gravity. The receptacle 10 fits freely within the container 11 and between the closures 14 and 15 and is moved during manipulation of the device. This keeps the passageway 32 clear and also assists in discharging powder into the same.

By the use of the felt disc 39, powder is prevented from siftin into the pumping chamber 45 and thus leaving the device from the wrong end of the same. I have found that due to the extreme length of travel of the air edgewise through the disc 49 when the flapper valve 41 is closed, that little or no air and powder escapes through said disc and into the chamber 45. When, however, the pressure is in the opposite direction,

valve 41 lifts and the air passes freely through the disc 39.

The advantages of our invention are manifest. By means of the construction disclosed, the powder may be sold in separate receptacles and these receptacles placed within the container for instant use. By merely perforating the holes in the wrapper of the receptacle and applying the enclosure to the container, the device is ready for use. In this manner, refills may be furnished without wasting of additional containers and pump cylinders. By the use of the felt disc, as disclosed, leakage of powder out of the device through the pump cylinder is entirely prevented.

Changes in the specific form of our invention as herein disclosed may be made within the scope of what is claimed without departing from the spirit of our invention.

Having described our invention, what we claim as new and desire to protect by Letters Patent is:

1. In a powder sprayer, a container comprising a sleeve and a fixed closure attached to one end thereof said container being open at its other end, a receptacle insertable into said sleeve through the open end thereof, said receptacle being closed at its ends, a removable closure for the open end of said container, said receptacle fitting freely within said sleeve to form an annular passageway therebetween and end chambers at the ends of said receptacle and adjacent said closures and communicating with said annular passageway, said receptacle floating within said container and having laterally extending powder discharge openings communicating with said annular passageway, an outlet opening in said removable closure communicating with the corresponding end chamber and pumping means at the end of the container having the fixed closure and communicating with the other of said end chambers.

2. In a powder sprayer, a container comprising a sleeve and a fixed closure attached to one end thereof said container being open at its other end, a receptacle insertable into said sleeve through the open end thereof, a removable closure for the open end of said container, said receptacle comprising a tubular wall structure and imperforate caps secured to the ends of said wall structure, said receptacle fitting freely within said sleeve to form an annular passageway therebetween and end chambers at the ends of said receptacle and adjacent said closures, said wall structure of the receptacle having laterally extending openings therein adjacent said caps and discharging into said annular passageway, an outlet opening in said removable closure communicating with the corresponding end chamber and pumping means at the end of said container having the fixed closure and communicating with the other of said end chambers.

3. In a powder sprayer, a container comprising a sleeve and a fixed closure attached to one end thereof said container being open at its other end, a receptacle insertable into said sleeve through the open end thereof, a removable closure for the open end of said container, said receptacle comprising a tubular wall structure and imperforate caps secured to the ends of said wall structure, said caps being identical in construction, said receptacle fitting freely within said sleeve to form an annular passageway therebetween and end chambers at the ends of said receptacle and adjacent said closures, said wall

structure of the receptacle having laterally extending openings therein adjacent said caps and discharging into said annular passageway, an outlet opening in said removable closure communicating with one of said end chambers and pumping means at the end of said container having the fixed closure and communicating with the other of said end chambers.

4. In a powder sprayer, a container cylindrical in form and comprising a sleeve and a closure attached to one end thereof, a receptacle closed at its ends within said container of similar configuration and of lesser external diameter and length than the internal diameter and length of said container, said container having an opening at its end opposite said closure through which said receptacle may be inserted into or removed from the container, a removable closure for said opening, said receptacle being spaced from the sleeve of the container to form an annular passageway therebetween and providing chambers at opposite ends of the container communicating with said passageway, a discharge outlet leading from one of said chambers, pumping means associated with the other of said chambers, said receptacle floating within said container and having laterally extending openings discharging into said annular passageway.

5. In a powder sprayer, a container cylindrical in form and comprising a sleeve and a closure attached to one end thereof, a receptacle closed at its ends within said container of similar configuration and of lesser external diameter and length than the internal diameter and length of said container, said container having an opening at its end opposite said closure through which said receptacle may be inserted into or removed from the container, a removable closure for said opening, said receptacle being spaced from the sleeve of the container to form an annular passageway therebetween and providing chambers at opposite ends of the container communicating with said passageway, a discharge outlet leading from one of said chambers, pumping means associated with the other of said chambers, said receptacle floating within said container and having a plurality of circumferentially arranged laterally extending openings discharging into said annular passageway, said openings being arranged so that at least one of said openings communicates with said passageway when the receptacle is resting upon the sleeve of the container.

6. In a powder sprayer, a container cylindrical in form and comprising a sleeve and a closure attached to one end thereof, a receptacle closed at its end within said container of similar configuration and of lesser external diameter and length than the internal diameter and length of said container, said container having an opening at its end opposite said closure through which said receptacle may be inserted into or removed from the container, a removable closure for said opening, said receptacle being spaced from the sleeve of the container to form an annular passageway therebetween and providing chambers at opposite ends of the container communicating with said passageway, a discharge outlet formed in one of said closures and communicating with one of said chambers, means for holding the closure in which said outlet is formed spaced from the corresponding end of said receptacle to permit of entry to and discharge from the chamber formed therebetween, pumping means associated with the other of said chambers, said receptacle floating

within said container and having laterally extending openings discharging into said annular passageway.

7. In a powder sprayer a receptacle comprising a tubular body portion, a cap for closing one end of said body portion and having a flange extending along and secured to said body portion, a container including a sleeve surrounding said body portion and spaced therefrom to form a passageway extending about said receptacle, said container being open at the end of the same at which said cap is disposed for the endwise reception of said receptacle, said body portion having openings therein discharging into said passageway, a closure for the open end of said container having a discharge opening therein and projections extending inwardly therefrom, a boss on said cap adapted to engage said projections to provide passageway between said cap and closure leading up to said discharge opening and pumping means for forcing air through all of said passageways.

8. In a powder sprayer a receptacle comprising a tubular body portion and end members attached thereto, a container including a sleeve surrounding said body portion and forming therewith an annular passageway, said container being open at one end for the endwise reception of said recep-

15
5
10

tacle, the tubular body portion of said receptacle having outlet openings communicating with said passageway, a closure attached to said sleeve and closing the open end of said container, said closure having an outlet opening therein, lugs on said closure engaging one end of the receptacle and forming a laterally extending passageway between said annular passageway and said outlet opening in said closure and means for forcing air through said passageways.
